SAFETY DETECTOR DEVICE FOR PIN INSULATORS

Filed April 19, 1928

Attorneys:

UNITED STATES PATENT OFFICE

CHARLES H. SPANGLER, OF READING, PENNSYLVANIA, ASSIGNOR TO METROPOLITAN EDISON COMPANY, OF READING, PENNSYLVANIA, A CORPORATION OF PENNSYLVANIA

SAFETY DETECTOR DEVICE FOR PIN INSULATORS

Application filed April 19, 1928. Serial No. 271,157.

My invention relates to safety testing devices for high tension electrical lines, and more specifically to an improved device for testing the pin insulators supporting said line. It essentially comprises a luminous detector tube mounted on a long standard or handle and provided with a pin contact and a controllable gap so that the operator from a safe distance may contact said point with the insulator and from the electrical action on the luminous tube determine the insulators that are properly functioning and those that are defective and need replacement. My improved structure is more fully described in connection with the accompanying drawings, and the novel features specifically set forth in the appended claim.

Fig. 1 is an elevation of a testing device embodying my improvements.

Fig. 2 is a greatly enlarged cross-sectional elevation of the luminous detector and its mounting on the upper end of the standard adjacent the pin contact carried thereby.

As shown in the drawings I employ a luminous detector device of the type indicated and more fully set forth in my prior Patent No. 1,701,196 issued February 5, 1929. The essential elements of said detector, as reference to the aforesaid application will disclose, comprise a gas filled tube 5 in an enclosing casing 6 having wall apertures 7, all mounted in an insulating open-end carrier tube 8 having a reflector 9 adjacent apertures 7, adapted to direct any luminous rays appearing in said apertures rearwardly through the window 10 in the open end of said casing. An inner carrier sleeve 11 is conductively connected with one end of tube 5 through tube support 12 and the opposite end of said tube, projecting into an insulating carrier end closure 13, is conductively connected to a right-angled contact 14 located in a side aperture formed in said closure 13.

In the present construction I mount the above described detector adjacent one end of a standard or handle 15, such mounting, as shown, comprising spaced apertured insulating plates 16 and 17; each of said plates having a midway parting and being clamped together by a screw bolt 18 to fixedly engage

and space the carrier 8 and standard 15 held in suitable plate apertures.

On the end of standard 15, and secured by screws 20, 20, passing through plate 16, is an insulating head 21 which carries a pin 55 contact piece 22 projecting from the end thereof and having a right-angled extension 23 projecting laterally from said head above said plate 16.

A gap closing screw 25, engaging a nut 60 26 as shown secured in plate 16, is adapted when properly turned to contact with extension 23 or be moved determinedly therefrom to break the flow of current to said screw. The plate 16 also has secured therein in a 65 suitable recess, a nut contacting block 27 with a backing spring, as shown, to conductively connect said screw to tube contact 14.

Screw 25 is conveniently adjusted by the operator grasping the lower end of said standard, through a screw operating extension comprising, as shown, a non-conducting tube or rod 28 secured at its upper end to screw 25, having a midway bearing in plate 17 and a lower bearing in a standard clamp 75 plate 29, and its projecting lower end provided with a knurled head 30.

In operation the standard is raised to insert its contact end 22 above the pin insulator skirt nearest the live wire carried thereby and the knurled head 30 turned until the diverted luminous ray seen through window 10 is brightest. Then the operator inserts the contact 22 below the aforesaid skirt, the luminous rays being reduced in the 85 case of a properly effective insulator, and requiring that the gap be closed by turning head 30 to secure bright luminous rays equal to those first secured.

Then the operator tries successive other skirts in succession, each, when in working order requiring further gap reduction as above, indicating effective insulation as desired. Should no reduction in the gap be required, then current is leaking past a skirt 95 and the insulator is partially or totally defective depending on the number of defective skirts.

My device depends on sight and the required number of turns of screw 25 to deter-

mine the safety or lack of safety of the insulator. As it is used outdoors in all kinds of weather it is not affected by wind howling or noise of passing traffic, and its long standard and visible ray readily seen at a secure distance therefrom make it a particularly convenient and simple device, readily transported and immediately operative under all conditions and at a safe distance from the tested line. The specific structure shown 10 may be readily modified within the scope of invention as defined in the following claim.

What I claim is:

A mounting for a safety tester device for high-tension-line pin-insulators comprising 15 a carrier standard having an insulating end-support for a pin contact, and spaced insulating supports for a detector device adjacent said end-support, a contact pin mounted in said end-support having a lateral projection therefrom and a vertical pin-insulator contacting projection, a ray-reflecting luminous detector device mounted in said spaced supports and having a laterally projecting contact pin, an engaging screw-threaded nut for the latter carried by one of said spaced supports, a gap-closing screw-pin mounted in said nut and adjustable from and toward said end-support lateral contact, 25 and an insulated screw-pin operating extension rod mounted parallel to said carrier standard and approximately coextensive in length with the latter.

In testimony whereof I affix my signature.

CHARLES H. SPANGLER.
